STRETCHABLE WASH STRAP
Palmerino C. La Falce, 99 17th St., Buffalo, N.Y.
Filed Feb. 8, 1961, Ser. No. 87,868
3 Claims. (Cl. 15—222)

This invention relates to an improved wash strap.

The primary object of the present invention is to provide a wash strap which is stretchable so as to render the same particularly useful for washing the user's back, while holding opposite ends of the strap and without requiring a change in location of grasping the strap.

Another object of the invention is to provide such a wash strap which has a facing of suitable material for washing the user's body regardless of which side or edge of the strap is held against the user's body.

Another object is to provide such a wash strap which when not in use provides a compact article and may thus be conveniently stored or relatively inconspicuously placed.

A further object is to provide such a wash strap which can be readily laundered.

Other objects are to provide such a wash strap which is simple in construction and easy to manufacture, and hence relatively inexpensive.

Still other objects and advantages of the present invention will be apparent from the following detailed description of a preferred embodiment thereof, illustrated in the accompanying drawings wherein:

FIG. 1 is a perspective view of the cloth material and elastic strip constituting the two principal components of the inventive wash strap and showing the same arranged flat and superimposed to represent the first stage of manufacture.

FIG. 2 is a similar view thereof but showing the cloth component folded upon itself to represent the second stage of manufacture.

FIG. 3 is a similar view thereof but showing the previously doubled cloth material turned inside out which provides a tube completely encasing the elastic strip to represent the third stage of manufacture, a portion of the cloth covering being broken away to expose hidden structure.

FIG. 4 is a similar view thereof but illustrating the intermediate portion of the cloth tube gathered over the elastic strip to represent the fourth stage of manufacture.

FIG. 5 is a similar view thereof and showing the cloth tube substantially flat and the elastic strip stretched to permit the application of transverse stitching, this view representing the fifth stage of manufacture.

FIG. 6 is a similar view thereof but representing the condition of the partly assembled wash strap shown in FIG. 5 with the elastic strip restored to a substantially unstretched condition.

FIGS. 7-10 are severally fragmentary perspective views of an end portion of the cloth tube which extends beyond the elastic strip therein, and represent sequentially the treatment of such end extension to form the same into a loop.

FIG. 11 is a perspective elevational view of a completely assembled wash strap embodying the present invention and constructed in accordance with the procedures illustrated in the previous figures.

FIG. 12 is a diminutive view, more or less schematic, and depicting the manner of use of the inventive wash strap by a person holding the strap so as to extend across her back.

The construction of a wash strap embodying the present invention, as shown in FIG. 11 and represented generally by the numeral 19, is believed best understood by tracing a preferred mode of manufacturing the same. Referring to FIG. 1, the numeral 20 represents an elongated rec-

2

tangular piece of suitable cloth material such as terry cloth, arranged in a flat condition. Shown superimposed thereon and adjacent one corner of the cloth piece 20 is an elongated rectangular elastic strip 21. The area of the rectangular elastic strip 21 is considerably less than that of the rectangular cloth piece 20. While this elastic strip 21 may be a rubber sheet or other suitable elastic material, it is preferably a stretchable fabric woven with textile fiber covered rubber threads or strands.

10 The elastic strip 21 is placed so that one end edge 22 thereof is spaced inwardly a distance 23 from the corresponding and parallel end edge 24 of the cloth piece 20. The elastic strip is secured to the cloth piece adjacent the end edge 22 of the strip in any suitable manner. As shown, this is preferably accomplished by stitching the two elements together, the row of stitching being indicated at 35. Also, one longitudinal edge 25 of the elastic strip 21 is placed relatively closely adjacent the corresponding and parallel longitudinal edge 26 of the cloth piece 20, such spacing being indicated at 28.

20 As shown in FIG. 1, the elastic strip 21 is in an unstretched condition to provide a relatively large spacing 29 between the other end edge 30 of this strip and the corresponding and parallel end edge 31 of the cloth piece 20. The other longitudinal edge 32 of the elastic strip 30 is located inwardly from the corresponding and parallel longitudinal edge 33 of the cloth piece 20, by a distance 34 which is equal approximately to the width of the elastic strip 21 plus the spacing 28. In other words, the edge 32 of the elastic strip lies approximately along the major centerline of the rectangular cloth piece 20.

25 Thereafter, the elongated half portion 36 of the cloth piece 20, uncovered by the elastic strip 21, is folded downwardly and reversely upon itself so that the longitudinal edges 26 and 33 of the cloth piece are conterminous, as shown in FIG. 2. The elastic strip 21 is still external of the two plies of cloth that are now formed. When in this condition, these plies are secured together along the edges 26 and 33 in any suitable manner. As shown, this is 30 preferably accomplished by stitching, the row of stitching being indicated at 38. The stitching 38 begins adjacent the end edge 31 of the cloth element, terminating short of the edge 31 by a distance 39 which corresponds dimensionally to the spacing 23. It will be noted that the row 35 of stitching 38 does not secure any portion of the elastic portion 21.

35 Following this, the tubular cloth article is turned inside out so that the elastic strip 21 is now arranged inside a cloth tube indicated generally at 40 in FIG. 3. This cloth tube now constitutes a covering for the elastic strip 21, not only completely surrounding or encasing the same but extending longitudinally beyond the ends of the elastic strip. The flattened tube 40 has a pair of flat sides or faces 41 and 42 which oppose the respective flat sides of the elastic strip 21. It will be noted that the marginal 40 portions along the edges 26 and 33 of the cloth piece 50 form an inverted hem indicated at 43. This hem 43 provides the seam for the cloth tube 40. The elastic strip 21 is now secured to both faces 41, 42 of the cloth tube 40 by an additional one or more rows of stitching 44 which 55 secure the two cloth faces and the intermediate elastic strip together.

60 As illustrated in FIG. 4, the intermediate portion of the cloth tube 40 is then gathered over the elastic strip 21 so that the end edge 30 of this elastic strip is arranged closer to the folded edge 31 of the cloth piece, specifically being set inwardly from this edge by the distance 39. With the edges 30 and 31 so positioned relatively to each other, the elastic strip and both faces 41 and 42 of the cloth tube are secured together suitably as by one or more 65 transverse rows of stitching 45 arranged adjacent the edge 30 of the elastic strip.

Following this, the cloth tube 40, with the elastic strip 21 therein and secured at opposite ends to the tube, is now flattened out thereby stretching the elastic strip, as shown in FIG. 5. With the article so positioned, additional transverse rows of stitching 46 are applied substantially across the full width of the elastic strip and at longitudinally spaced intervals therealong, preferably uniform, intermediate the end securements provided by the rows of stitching 44 and 45. Any other suitable manner of achieving the intermediate transverse securements may be employed but the stitching 46 is preferred.

After the intermediate transverse rows of stitching 46 have been applied to secure both faces 41 and 42 to the elastic strip 21, the article may be allowed to assume a normal position as represented in FIG. 6 in which the elastic strip 21 is unstretched or substantially so. It will be noted from a comparison of FIGS. 5 and 6 that in returning to an unstretched condition of the elastic strip 21, the portion of the cloth material intermediate the adjacent parallel rows of stitching 44-46 is gathered or bunched into folds, as represented at 48, so that the intermediate portion of the wash strap covering assumes a corrugated configuration. However, these folds or gathers 48 tend to flatten out when the strap is elongated in its major direction by stretching the internally arranged elastic strip 21.

Hand hold means are provided at opposite ends of the wash strap. While such means may be otherwise provided, the extensions indicated at 49 at opposite ends of the wash strap are conveniently used for at least part of such means. As illustrated, the extension 49 at each end of the strap is formed into a loop 50 for the reception of a ring 51 which is preferably split or otherwise suitably constructed so that it may be removed from its loop 50 when the wash strap is laundered.

Formation of one of the loops 50 will now be described. Referring to FIG. 7, the extension 49 is slit along the fold in the cloth material, as represented at 52. This slit 52 extends from the outer end of the extension 49 back to a point about opposite the end edge 22 of the elastic strip 21. Thus, an upper flap 53 and a lower flap 54 are provided.

Referring to FIG. 8, the longitudinal marginal portions 55, 55 of the lower flap 54 are folded upwardly and inwardly and arranged so that the outer end of the flap 54 is narrower than its inner end. Any suitable means for securing the marginal folds 55 to the main body of the flap 54 may be employed. As shown, this is preferably accomplished by a row of stitching 56. The same treatment is given to the upper or other flap 53. The completed condition of the upper flap 53 thereof is represented in FIG. 9.

Following this, the flaps 53 and 54 are twisted so that the flat sides or backs thereof oppose each other. This is illustrated in FIG. 10. The flaps adjacent their outer ends are then secured together in any suitable manner as by stitching the same together, a row of stitching for this purpose being indicated at 58 in FIG. 10. Thereafter the secured flaps can be untwisted, resulting in a loop 50 open at opposite sides or ends and adapted to receive a ring 51 passing therethrough.

Referring to FIG. 11, it will be observed that the completed wash strap is relatively short and comprises an elastic strip completely encased by a covering of cloth material secured to the elastic strip in such manner that a wrinkled effective washing surface is provided on each side of the stretchable strap.

As depicted in FIG. 12, typically the user grasps the rings 51 and places the strap across her back at the desired angle, manipulating the ends into the desired position and spaced apart a comfortable distance, within the

maximum limits permitted by the wash strap when in a fully stretched condition. When so held, the wash strap can be slid back and forth over the body surface by moving the arms and repositioning the strap as desired to cover different areas of the body. It will be seen that the elasticity of the strap maintains the same in full area contact with the body even though the effective spacing between the hand hold means is varied to suit the physique and desires of the user.

When the wash strap is to be laundered, the rings 51 may be removed as is preferred so that these rings, which may be made typically of a suitable plastic material or metal, will either not be damaged themselves nor damage the washing machine during the laundering operation.

From the foregoing, it will be seen that the preferred embodiment of the present invention provides a wash strap which achieves the various objectives stated. Modifications and changes in the construction of the particular wash strap illustrated and described may occur to those skilled in the art. Accordingly, the embodiment shown and described is illustrative and not limitative of the invention, the scope of which is to be measured by the appended claims.

What is claimed is:

1. A wash strap, comprising an elongated elastic strip having opposite sides, a covering of cloth material surrounding said strip and including faces opposing said sides, means securing said faces to said strip substantially across the full width of said strip and at longitudinally spaced intervals therealong, the cloth material of said covering being gathered between such transverse securements when said strip is substantially unstretched and tending to flatten out when said strip is stretched, and hand hold means at opposite ends of said covering.

35 2. A wash strap, comprising an elongated elastic strip having opposite sides, a covering of cloth material surrounding said strip and including faces opposing said sides, means securing said faces to said strip substantially across the full width of said strip and at longitudinally spaced intervals therealong, the cloth material of said covering being gathered between such transverse securements when said strip is substantially unstretched and tending to flatten out when said strip is stretched, and hand hold means at opposite ends of said covering including loops of cloth material as extensions of said covering and rings passing through said loops.

40 3. A wash strap, comprising an elongated elastic strip having opposite ends and opposite sides, a covering of cloth material encasing said strip and extending beyond said ends and including faces opposing said sides, rows of stitching securing said faces to said strip and severally extending substantially across the full width of said strip and arranged at longitudinally spaced intervals therealong, the cloth material of said covering being gathered between such transverse stitching when said strip is substantially unstretched and tending to flatten out when said strip is stretched, the portions of said covering of cloth material beyond said ends of said strip forming loops, and removable rings passing through said loops for hand hold purposes.
